UNITED STATES PATENT OFFICE.

ALFRED KNOWLES, OF CHEETHAM, MANCHESTER, ENGLAND.

MEANS FOR PRESSING AND FINISHING CLOTH CAPS.

1,069,337.

Specification of Letters Patent.

Patented Aug. 5, 1913.

Application filed July 20, 1912. Serial No. 710,664.

To all whom it may concern:

Be it known that I, ALFRED KNOWLES, subject of the King of Great Britain and Ireland, and resident of Cheetham, Manchester, in the county of Lancaster, England, have invented certain new and useful Improvements in Means for Pressing and Finishing Cloth Caps, of which the following is a specification.

10 My invention relates to improvements in means for pressing and finishing cloth caps and more particularly to those of the peaked variety, the object being to provide mechanical means by which the whole of the cap 15 can be pressed and finished at one operation.

Prior to the date of my invention caps of the type referred to have, so far as I am aware, always been pressed and finished by 20 hand, that is to say, by ironing with the usual types of heated irons, a process which is not only laborious but slow.

The object of my invention is to avoid the 25 defects of the method referred to by providing means by which peaked caps mainly may be pressed in that type of press which is used for the pressing of felt hats, helmets and the like.

My invention will be fully described with 30 reference to the accompanying drawings in which,

Figure 1 is a sectional front elevation showing my improvements applied to a press of the type referred to, Fig. 2 plan 35 of same and Figs. 3 and 4 similar views to Figs. 1 and 2 of a modified arrangement of the device.

In the aforementioned drawings *a* indicates a portion of the bed or table of a hat 40 press and *b* and *c* the upper and lower portions, respectively, of a box used in such press, which is movable up and down by the ordinary well known means. The two parts 45 of the box have secured between them so as to make a water tight joint an indiarubber bag *d* which is held in position by bolts *e*, set-screws or the like.

My invention consists in the provision of 50 a new construction of dish adapted to be employed in a press such as hereinbefore mentioned, such dish being formed to embrace the outside of the cap and enable the whole of the body as well as the peak to be pressed and finished at a single operation. Peaked caps, as is well known, consist of a band or portion *f* which fits the

head while the main body *g*, or in other words the crown, extends from this upwardly and usually bulges outwardly, as at *h* to considerably larger diameter, the front 60 of such bulging portion being usually fastened to the visor *i* by a spring button fastener or other suitable device. It is on account of this bulging-out portion and its connection with the peak that difficulties 65 have presented themselves in the arrangement of suitable means for effecting mechanical pressing.

My invention therefore, consists in a dish usually formed in two main parts an upper and a lower portion, such lower or base portion *j* being provided with an integral flanged portion *k*. The flanged portion fits in a hole formed in the table *a* and is shaped as indicated in the drawings to correspond 70 with the upper portion of the bulging section of the cap, the latter being shown in reverse position in Figs. 1 and 2. The second main portion of the dish is made in halves *m* and *n* as indicated in the figures, 75 although the portion *m* may be formed integral with the lower dish portion *j*.

The portions *m* and *n* are much easier to make and are most effective in use when 80 made in two separate parts as shown in the drawings and adapted to be fitted in the lower portion *j*, such as by a recess *o* and extending ring *p*, the joint being preferably 85 slightly tapered so as to provide a good fit. The portion *n* is provided with an extending flange or block *q* of substantially the same shape as the visor of the cap in plan so that such visor may rest thereon and be 90 pressed as well as the other portions of the cap. Where caps having a visor at back 95 and front are to be pressed a similar block *r* is formed on the portion *m*, as indicated in broken lines in Fig. 1. The interior surface of the parts *m* and *n* is shaped to correspond with the lower part of the bulging portion of the cap and with the band portion which fits the head. The forming of 100 the top portion of the dish in two parts *m* and *n* is to enable a peaked cap to be placed in the dish easily and to be withdrawn therefrom after pressing without disturbing its pressed shape.

Thus prior to the usual box portion *b* and *c* being lowered on to the table *a* with its indiarubber bag *d*, the cap is placed in position by first taking away 105 the portion *m* and by then pushing the cap into position with its visor on the block *q* 110

and the body portion resting in the dish *j*. The part *m* can then be placed in position and the usual pressing operation take place by lowering the box *b*, *c* and indiarubber bag *d* and afterward admitting hydraulic pressure within the box and dish so enabling the rubber bag to press all parts of the cap including the peak in the dish or mold as will be well understood. The indiarubber bag is indicated by the black section. The dish *j* is heated in the usual way to the dishes employed in the felt hat pressing machines previously referred to. The result of the operation is to give a perfect finish to the cap, the box and indiarubber bag being subsequently raised and the cap withdrawn by taking away one half of the mold *m* in the manner previously described.

The portion of the mold *n* may be made in one with the lower portion *j* while the portion *m* may be loose as previously described and may be hinged to the portion *n*.

In Figs. 3 and 4 a modification of the device is shown for use in pressing caps without visors. The device is constructed as previously described with the exception that the extension for supporting the visor during pressing is dispensed with. The upper portion of the dish may be made in two parts *m* and *n* forming a complete ring and may be manipulated in the manner previously described. On the other hand such parts may be made in one piece or ring since the cap after pressing can be removed from the underside of the ring after lifting the latter away from the lower portion *j*. The upper portion of the dish, that is to say the parts *m* and *n* may be made in more than two parts. The band of the cap may be held in position against the parts *m* and *n* while the indiarubber bag descends into the cavity of the dish by means of removable metal clips *s*.

The arrangements of device hereinbefore described enable caps to be thoroughly pressed in much quicker time and with better results than is the case with hand pressing.

What I claim as my invention and desire to secure by Letters Patent is:—

1. In a press for cloth caps, the combination, with a dish comprising a lower portion and a separable upper portion, the lower portion being provided with a mold for the crown of the cap, and the upper portion having a mold for the band of the cap of smaller size than the crown mold and having means

for locating it in position on the crown mold, of a press box provided with an extensible bag adapted to fit over the said upper portion and engage with the inside of the cap. 60

2. In a press for cloth caps, the combination, with a dish comprising a lower portion and a separable upper portion, the lower portion being provided with a mold 65 for the crown of the cap, and the upper portion having a mold for the band of the cap of smaller size than the crown mold and having means for locating it in position on the crown mold, and said upper portion being 70 formed of separable sections, of a press box provided with an extensible bag adapted to fit over the said upper portion and engage with the inside of the cap.

3. In a press for cloth caps, the combination, with a mold provided with a crown portion and a band portion of smaller size than the crown portion, said band portion having a separable section, so that the cap may be inserted in and removed from the 80 mold, and said separable section being provided with means for locating it in position in the mold, of a press box provided with an extensible bag adapted to fit over the band portion of the mold and engage with 85 the inside of the cap.

4. In a press for cloth caps, the combination, with a supporting table provided with a recess, of a dish comprising a lower portion and a separable upper ring formed of 90 separable sections, said lower portion having a flange which engages with the said recess, and having also a concave mold for the top of the crown of the cap, and said upper ring having inwardly and upwardly curved portions which overlap the concave mold and which form a mold for the lower part of the crown and the head band of the cap, and one of the ring sections having a block on its outer side which forms a mold for the visor 100 of the cap, a press box which rests on the table around the said ring, and an extensible bag secured to the press box and arranged to bear on the said flange and the outer part of the ring and to press the cap and its visor 105 in a single operation against the aforesaid molds.

In testimony whereof I have hereunto set my hand in the presence of two witnesses.

ALFRED KNOWLES.
